ALBERT E. MILLER, OF WESTFIELD, NEW JERSEY, ASSIGNOR TO SINCLAIR REFINING COMPANY, OF NEW YORK, N. Y., A CORPORATION OF MAINE.

DISTILLATION OF OIL.

Application filed June 11, 1927. Serial No. 198,124.

This invention relates to improvements in the distillation of heavy petroleum distillates and residues for the production of lighter oils, particularly gasoline, therefrom. The invention includes improvements in apparatus as well as improvements in process.

In carrying out the process of the invention, heavy petroleum distillates or residues are heated and distilled while in intimate contact with fuller's earth. The heated body of oil undergoing distillation is maintained at a temperature between about 575° F. and 650° F. The distillation is carried out under substantially atmospheric pressure. The oil supplied to the distillation is, with advantage, stripped of any light components it may contain. A body of fuller's earth substantially coextensive with the heated body of oil is maintained in contact therewith during the heating and distillation.

At temperatures between about 575° F. and 650° F. fuller's earth apparently has a catalytic action upon petroleum oils which promotes reactions producing lighter oils of a gasoline character therefrom. At lower temperatures this action seems to be inconsequential in extent if it takes place at all. At higher temperatures decomposition as an effect of heat alone begins to be substantial in extent and, unless the operation is otherwise controlled, as for example by the imposition of superatmospheric pressures, heavier oils tend to escape by vaporization without the desired production of lighter oils. Operation under substantially atmospheric pressure is one of the advantages of this invention.

Another advantage of the invention is the maintenance of intimate contact between the fuller's earth and the oil undergoing distillation for a maximum period of time. This intimate contact between earth and oil for a maximum period of time is promoted by maintaining the earth body in contact with the oil substantially coextensive therewith and also by keeping the heavy oil supplied to the operation free from any large amount of light components vaporizing rapidly at the operating temperature. It is advantageous to keep the oil supplied to the operation substantially free from such light components, at least from more than a minor proportion of such components.

Although the body of fuller's earth is maintained substantially coextensive with the body of oil undergoing distillation, the body of earth is maintained free from contact with

walls of the still through which heat is transmitted, avoiding any tendency to reduce the rate of heat absorption by the oil at such heated walls either by any insulating effect of the fuller's earth or by any insulating effect of carbonaceous material deposited in the fuller's earth. In addition to the catalytic action mentioned above, the fuller's earth apparently absorbs in a selective manner heavy pitch-like products of the reaction, particularly the more objectionable of such materials such as those containing sulphur. The fuller's earth thus also assists in reducing corrosion and in reducing the deposition of carbon or coke or heavy carbonaceous material on the walls through which heat is transmitted.

The invention is particularly applicable to the distillation of heavy distillates and residues, such as heavy gas oil from heavy crude petroleums such as those from Mexico, California and Texas, fuel oil, reduced crude oil, and other heavy distillation residues.

In the treatment of crude petroleum oils in accordance with the invention, the crude oil is stripped of light oils, particularly those such as produced by the distillation in contact with fuller's earth, before the oil is subjected to the fuller's earth distillation treatment. The fuller's earth distillation treatment, for example, may with advantage be carried out in conjunction with a topping process, the residue from the topping process being supplied to the fuller's earth distillation treatment.

In carrying out the invention, the oil vapors driven off from the heated body of oil in contact substantially throughout the fuller's earth may be subjected to a refluxing operation, and where the heating operation is combined with a refluxing operation it is likewise advantageous to strip the reflux condensate of any light oils before returning it to the fuller's earth distillation treatment. The reflux condensate from such refluxing operation, for example, may be returned first to a topping still in which light oil is separated as vapor and from which the distillation residue is supplied to the fuller's earth distillation treatment.

By relieving the oil supplied to the fuller's earth distillation treatment of all light oils which vaporize rapidly at the temperature at which the body of oil in the fuller's earth distillation treatment is maintained, loss of heat in the still in which this operation is carried out through vaporization of such com-

ponents before these components have been in contact with the earth for a sufficient time to permit the earth to have had its full effect is avoided.

5 The invention will be further described in connection with the accompanying drawings, illustrating in a diagrammatic and somewhat conventional manner an apparatus embodying the invention and adapted for the 10 practice of the process of the invention, but it is intended and will be understood that the invention is illustrated thereby, not limited thereto.

Referring to the drawings, the still in 15 which the fuller's earth distillation treatment is carried out is shown at 11 mounted in a suitable furnace setting 12. It is advantageous to use a vertical type of still, as illustrated, in order to provide a relatively 20 deep bed of earth in contact with the oil undergoing treatment. A supporting screen 13 extending entirely across the still is arranged a short distance above the still bottom. The body of fuller's earth in the still 25 is supported by this screen and is thus kept free from the heated still bottom. An additional supporting screen 14 may be provided at an intermediate point in this still to relieve the lower supporting screen of part 30 of the weight of the earth bed. Supplementary support 17 may also be provided for this purpose. The body of earth in the still extends approximately to the normal liquid level so that in operation the surface 35 of the body of the earth is substantially coincidental with the oil level in the still. Manholes 15 are provided for access to the still. Vents 18 extending from below the lower screen to above the normal liquid level may 40 be provided to prevent the formation of gas or vapor pockets below the lower supporting screen 13. A discharge outlet from the still is shown at 19 and a level indicator at 16.

Oil is supplied to the still 11 through 45 connection 29, arranged to discharge into the space between the still bottom and the lower supporting screen 13. The oil is thus compelled to pass through the earth bed before it can escape as vapor. For better distribution, incoming oil may be introduced through 50 a hub and spoke distributing device 30. Vapors generated in this still are conducted to the lower part of the reflux tower 20 through pipe 21. Vapors remaining uncondensed escape from the reflux tower through 55 connection 22 to suitable condensing and collecting apparatus. Reflux condensate escapes from the reflux tower through connection 23. This reflux condensate may be returned to 60 still 11, in whole or in part, through connection 26, but more advantageously it is subjected to a stripping operation to relieve it of all light components before being returned to still 11.

65 One suitable form of apparatus for strip-

ping heavy oils of light components in carrying out the invention is shown in the drawing at the left of still 11. Many forms of apparatus may be used for this purpose. The apparatus illustrated comprises a series of 70 stills, 1 and 2, of ordinary shell construction mounted in suitable furnace settings 3. These stills are shown in stepped relation to permit gravity flow of unvaporized oil from still 1 to still 2, higher temperatures being maintained 75 in still 2 in operation. While but two stills are shown in this series, any necessary or desired number may be used. In the application of the invention to crude oils, the number of stills in the series may for example correspond to the number of cuts to be taken off before the residue is subjected to the fuller's earth distillation treatment. In the stripping apparatus illustrated, each still is shown as provided with a dephlegmator 4 through 80 which the vapors escaping from each still pass on their way to suitable condensing and collecting apparatus. In the operation of the stripping apparatus illustrated, fresh oil to be treated is supplied through connection 5, 85 provided with regulating valve 6, and the oil remaining unvaporized in still 1 flows through connection 7, provided with regulating valve 8, to still 2, from which oil remaining unvaporized may be supplied to the 90 fuller's earth distillation treatment through connection 31. Still 2 is also shown as provided with a draw off connection 9 having a regulating valve 10. In combined operation 95 of the stripping stills and the fuller's earth 100 still, distillation residue from still 2 may be withdrawn through connection 31 by pump 28 and introduced into still 11 through connection 29. Additional oil, of appropriate character, may also be supplied to still 11 by 105 means of pump 28 through connection 32. Reflux condensate to be stripped of light components, in the apparatus illustrated, is conveyed from the reflux tower 20 through connection 23 and trap 25, arranged to prevent 110 vapors from still 2 entering the reflux tower 20, and connection 24 provided with regulating valve 33 to still 2. Direct return of reflux condensate from the tower 20 to still 11 is provided for through connections 26 and 27 provided with regulating valve 36. Valves 34, 35 and 37 are provided for control of the supply of heavy oil to still 11. 115

The following example of one particularly 120 advantageous method of operation carried out in the apparatus shown in the drawings will illustrate the process of the invention: Oil is supplied to still 1 through connection 5 and heavy oil remaining unvaporized in still 1 is discharged through connection 7 to still 2. The firing of stills 1 and 2 is regulated and the dephlegmators 4 are controlled, for example, to maintain the temperature of the vapors leaving the dephlegmator on still 1 at 125 about 400° F. and the temperature of the va- 130

pors leaving the dephlegmator on the still 2 at about 450° F. Heavy unvaporized oil from which the lighter components have been removed is withdrawn from still 2 by pump 28 and introduced into still 11 between the bottom of the earth bed and the bottom of the still. An oil level approximating the level of the bed of earth is maintained in still 11. The firing of this still is regulated to maintain the temperature of the oil body in the still between about 575° F. and 650° F. The rate of introduction of heavy oil to still 11, for example, is advantageously maintained at about 4% per hour of the normal still charge. For the direct production of a gasoline character fraction, the operation of the reflux tower may be regulated to maintain the temperature of the vapors escaping through connection 22, for example, at approximately 400° F. In this case, all of the reflux condensate is with advantage returned to still 2 from which, after removal of lighter components boiling off below the temperature range through which the fuller's earth is particularly active, the unvaporized residue from the reflux condensate is returned to still 11. Under these conditions, an additional yield of as much as 15% to 25% of gasoline may be obtained from the heavy oil charged to still 11.

The temperature of the vapors escaping through connection 22 may be maintained at a higher value and the vapors subsequently fractionated or condensed and the condensate redistilled for the separation of a gasoline character distillate. The temperature of the vapors escaping through connection 22, for example, may be maintained so high that the reflux condensate in tower 20 is relatively free from lighter components boiling below the range of temperatures through which the fuller's earth is particularly active, in which case the reflux condensate containing only the heavier components of the vapors escaping from still 11 may be returned directly to still 11.

Although operation in accordance with the invention is not indefinitely continuous, the fuller's earth remains active through remarkably long periods of time within the range of operating temperatures specified.

The combined operation of the invention, in which reflux condensate from the refluxing operation to which vapors from the fuller's earth distillation treatment are subjected is returned to a stripping operation for the removal of light components and from which unvaporized oil including the heavier components of such reflux condensate is supplied to the fuller's earth distillation treatment is advantageously carried out, as in the apparatus illustrated in the drawings, so that there is no substantial loss of heat available in the reflux condensate.

The combined operation of the invention

in which the light components are stripped from the crude oil together with the reflux condensate from the fuller's earth distillation treatment and the unvaporized heavy oil from the stripping operation supplied directly to the fuller's earth distillation treatment as in the apparatus illustrated in the drawings also provides that the fresh oil be supplied to the earth treatment at substantially the temperature at which the oil body is maintained during the earth treatment thus greatly increasing the capacity of the latter as well as the efficiency of the system as a whole.

I claim:

1. An improvement in the distillation of heavy petroleum distillates and residues for the production of gasoline therefrom, which comprises maintaining a body of the heavy oil at a temperature between about 575° F. and 650° F. in contact with a body of fuller's earth substantially coextensive therewith, taking off vapors from said body of oil and subjecting them to a refluxing operation, taking off vapors including gasoline components from the refluxing operation, stripping reflux condensate from the refluxing operation of light components, and returning reflux condensate from which light components have been so stripped to the first said body of oil.

2. An improvement in the distillation of heavy petroleum oils for the production of gasoline therefrom, which comprises maintaining a body of the heavy oil at a temperature between about 575 degrees F. and 650 degrees F. in contact with a body of fuller's earth substantially coextensive therewith, stripping heavy petroleum oils of light components and supplying heavy unvaporized oil from the stripping operation to maintain said oil body while distilling gasoline therefrom at substantially atmospheric pressure.

3. An improvement in the distillation of heavy petroleum oils for the production of gasoline therefrom, which comprises maintaining a body of the heavy oil at a temperature of between about 575 degrees F. and 650 degrees F. in contact with a body of fuller's earth substantially coextensive therewith, taking off vapors from said body of oil and subjecting them to a refluxing operation, taking off vapors including gasoline components from the refluxing operation, stripping the reflux condensate from said refluxing operation together with fresh heavy oil of light components and supplying the unvaporized oil from which the light components have been so stripped to the first said body of oil.

In testimony whereof, I have subscribed my name.

ALBERT E. MILLER.
